UNITED STATES PATENT OFFICE.

HERMAN P. RUF, OF NEW YORK, N. Y.

TAPE OR BRAID WINDER.

Application filed November 30, 1925. Serial No. 72,115.

This invention relates to textile machinery and has particular reference to tape or braid winding machines.

Among the objects of this invention is to provide a tape or braid winding machine which is of particularly simple construction so as to be relatively inexpensive to manufacture and to be wholly reliable in operation, said machine including various novel features such as, for instance, means for facilitating the forming of a skein of braid or tape which is tightly wound and in such manner as to be retained in good condition in shipment, and means for automatically stopping the machine after such skein has been completed.

Another object of this invention is to provide a tape winding machine or the like which is of novel mechanical construction to facilitate the rapid winding of tape or the like into a skein and with the desirable degree of uniformity and tightness to secure the maximum uniformity of appearance, such machine comprising a minimum number of moving parts which are so arranged with respect to each other as to secure the maximum reliability.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a plan view of the machine showing the same at the moment of beginning a new winding in the course of the formation of a skein of tape.

Fig. 2 is a detail view showing the drive mechanism and with one of the locking members in dotted lines.

Fig. 3 is a section substantially on the line 3—3 of Fig. 1.

Fig. 4 is a side elevation of the machine as indicated by arrows 4—4 of Fig. 1.

Fig. 5 is a detail view with parts in section showing certain of the locking mechanism.

Fig. 6 is a sectional view on the line 6—6

of Fig. 5 and showing another feature of the locking mechanism.

Fig. 7 is a view similar to Fig. 6, but with the locking mechanism operated to stop the machine.

Fig. 8 is a view in elevation showing an arm of the reel.

Fig. 9 is a sectional view on the line 9—9 of Fig. 8.

Fig. 10 is a sectional view on the line 10—10 of Fig. 8.

Fig. 11 is a detail sectional view on the line 11—11 of Fig. 3.

Referring now more specifically to the drawings, I show my machine as comprising a reel including a plurality of spaced parallel arms 12 which are supported in any suitable manner as by means of a bar or frame 13 which is rotatable about a shaft 14. The arms of the reel are secured to said frame in any suitable manner as by means of anchor members 15, said anchor members being bolted to the frame through slots 16 so as to be movable along said frame for adjustment of said arms toward or away from each other according to the size of the skein to be formed. The shaft 14 constitutes the

main drive shaft of the device and is journaled in bearings 17 and 18 which are fixed upon the frame 19 of the machine. Journaled freely on said drive shaft is a pulley 20 which has a groove to receive a belt 21, a disk 22 being provided to have frictional engagement with said pulley as by means of a friction gasket 23 inserted directly therebetween. The disk 22 has a hub 24 which has connection with the drive shaft by means of a spline 25. A spring 26 mounted upon said shaft is provided for actuating the disk 22 into frictional engagement with the gasket 23 while the spline 25 permits of suitable movement of said friction disk along the shaft for this purpose. Suitable drive means such as a worm 27 is fixed rigidly to the drive shaft, and preferably for the sake of simplicity of construction, the spring 26 has direct abutment relation against said worm at one end thereof and at the other against the hub 24. It is clear that when the belt 21 operates as, for instance, in the direction of arrow *a*, that a torque will be transmitted through the gasket 23 and hub 24 and thence to the worm 27; the reel being mounted up-

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

on the drive shaft is rotated directly thereby, while other parts in the operating mechanism that will be described hereinafter are actuated from the worm 27.

5 The reel may assume such form as is feasible with the main idea of this invention as will be indicated hereinafter. I have found it desirable to provide the arms 12 with grooves 28 extending along the outer 10 edge surfaces of said arms remote from each other, the groove being deepened as shown at 29 at the free end of each of said arms, the side portions of said arms about said groove at 29 being bent somewhat toward 15 each other, thus forming a reliable spring clamp. It will now be seen that a cord 30 can be readily placed in position in said groove, one end thereof being clamped at 29 and the other by any suitable spring clamp 20 31 which is positioned upon the fixed end of each of said arms. Before the tape T is to be wound upon the reel, cords 30 are placed in position as described, and then the skein is formed and after being completed, the 25 strings may be tied about the skein before removing the same from said arms. Inasmuch as these cords are positioned at the ends of the skein, they provide a reliable fastening therefor.

30 The tape is wound on the reel at one portion thereof forming a winding of a certain number of turns and then the tape is supplied to another portion of the reel preferably immediately adjacent to the winding 35 last formed and a new winding is formed thereon, continuing in this manner until the skein is completed. A guide 32 is so arranged as to be movable relatively to said reel. Preferably the guide is mounted upon 40 a shifter bar 33 which carries a rack 34 and is preferably cut directly into said bar, a cam 35 being operative to move said bar whenever a new winding of tape is to be formed upon the reel. It will be understood 45 that the pitch of a tooth of said rack will be equal to the width of the tape. Likewise that the pitch of the cam will be equal to the width of the tape so that every time the bar shifts the guide will be moved just 50 enough to feed the tape to a portion immediately adjacent the winding last formed. The cam 35 is for the sake of simplicity of construction supported upon the shaft 14 so as to be rotatable about the axis of the reel, said 55 cam being secured to the frame 13 of the reel as by means of screws 36 and a supporting bar 37 which is fastened to the hub 38 of the reel. It follows consequently that the cam 35 makes a complete rotation every 60 time that the reel rotates. However, inasmuch as it is undesirable to have the tape shifted to a new position along the reel every time that a turn is made, the bar 33 is positioned preferably in spaced relation to the 65 cam and with the teeth thereof out of mesh-

ing engagement as shown in Fig. 4 so that the cam is inoperative to move the bar and consequently the guide 32. However, the shifter bar is arranged to be movable toward the cam periodically as, for instance, 70 after a predetermined number of turns of tape have been formed upon the reel at one particular portion thereof, it being then desirable to begin a new winding as shown in Fig. 1. The means for mounting the bar in 75 said manner and for causing such movement of the bar transversely to the axis of the cam 35 may assume any suitable form. However, I prefer to use a worm wheel 39 which has meshing engagement with the 80 worm 27 and carries a suitable actuating member or cam 40 which co-operates with a follower 41 to cause a transverse movement of the shifter bar as aforesaid every time that the worm wheel completes a revolution. 85 It is clear that the gear ratio as between the worm and the worm wheel will control as to the number of turns of tape formed upon the wheel before a new winding is put on, and that the bar 33 moves in constant 90 parallelism to the axis of the cam 35.

The worm wheel 39 has a hub 42 which is secured to a shaft 43 journaled in a bearing 44, a collar 45 being used to retain the 95 shaft in its proper place within the bearing. The cam 40 is mounted rigidly upon the hub 42 and has working contact along a comparatively steep surface 46 on the follower 41. It is obvious that actuation of the 100 follower 41 by the cam must occur through a relatively small angular movement of the worm wheel as determined by the size of one of the teeth thereon inasmuch as rotation of the worm wheel through such angular distance is caused by one complete rotation of 105 the worm. The shifter bar 33 is movable in any suitable manner toward or away from the cam 35 when the follower is actuated by the cam. Preferably, however, for the sake of simplicity of construction, a bracket 47 110 is provided which is arranged to rock upon a bearing or shaft 48 which is mounted within the bearing supports 49^a upon the frame of the machine. The bracket 47 includes a 115 guide or housing portion 49 for the shifter bar and an auxiliary stationary supporting member or bar 50 acts as reinforcement for the shifter bar. A cover plate 51 is secured to the guide portion 49 as by means of screws or the like to retain the shifter bar in 120 reliable slidable position. The lower end of the bracket 47 is provided with a holder portion 52 within which the follower 41 is 125 movable longitudinally and generally transversely to the axis of the reel. The follower is provided with a key way 53 and a screw or pin 54 has co-operation therein to prevent rotation of the follower. The screw 55 is used to lock the follower against longitudinal movement in the holder 52. The follow- 130

er is thus adjustable to suit any operating conditions and to obtain a precise adjustment for maximum efficiency of operation.

Co-operating with the cam 40 is a spring 56 which is secured at one end to the frame of the machine and at the other end to a portion of the bracket 47 so as to be operative to tilt or rock the bracket toward vertical position as shown in Fig. 4 and with the 10 rack of the shifter bar out of engagement with the cam 35. When this occurs, the working face 46 on the follower will be positioned directly in the path of the cam 40 so as to be readily actuated thereby. A 15 stop 57 is secured to the frame of the machine and operative to limit the tilting movement of the bracket under actuation of the spring 56.

The guide member 49 is provided with 20 automatic or resilient means to engage the shifter bar 33 and retain the same and consequently the guide 32 in relatively fixed position while tape is being wound upon the reel at one portion thereof. This means 25 takes preferably the form of a spring 58 while the shifter bar is provided with a series of grooves or recesses 59 along an edge surface thereof opposite to the rack 34, the pitch of said grooves being equal to the 30 pitch of the rack teeth. Consequently when the cam 35 operates to move the bar longitudinally for starting a new winding of tape on the reel, the spring 58 snaps into a new notch or groove and is effective for 35 retaining the bar against unintended movement until the winding at the particular portion of the reel is completed. Moreover, assuming that the entire skein on the reel has been wound and a new skein is about 40 to be begun, the bar 33 is readily moved through its supporting member or guide 49 back into initial position and against the force of the spring 58 which will then slip in and out of the series of notches. To facilitate 45 such manual movement or actuation of the bar, a handle which may take the form of an upright rod 60 is provided secured rigidly to the shifter bar.

My invention includes novel means for 50 automatically stopping the machine after a skein has been completed. However, conforming to my object for providing a machine of maximum simplicity, I have devised a novel arrangement of parts having 55 particularly simple and easy co-operation with the other and main members of the machine. For bringing the machine automatically to a stop, I use a bar 61 which is movable or tiltable about the shaft 48 as 60 an axis and is provided with a cam surface 62 to wedge or engage with the projection 63 which is formed integrally on the hub 24 of the disk 22. While the machine 65 is operating in its normal manner, the bar 61 is preferably positioned in spaced rela-

tion to the hub 24. However, when the machine is to be stopped, said bar or lever drops, thus permitting the cam surface 62 to engage or wedge against a projection 63, and inasmuch as the direction of rotation 70 of the operating mechanism is as indicated by arrow α , it is clear that the machine will immediately be brought to a stop, the clutch mechanism being then inoperative. The operator may then come along and throw 75 the belt 21 off or release another clutch as may be desired to release the clutch member 23 from further strain. During normal operation of the machine suitable locking mechanism is provided to retain the lever 61 in upright spaced relation as aforesaid, 80 said locking mechanism including a trip member which is arranged to be actuated by the shifter bar 33 after the same has moved outwardly to its predetermined position of motion. More specifically, a bell crank 63^a is provided which is tiltable about a pin or screw 64 while the hub 65 of the lever 61 is provided with a projecting portion 66 which is arranged to lock behind 85 an arm 67 of the bell crank as is clearly shown in Fig. 6. A spring 68 is operative to throw the bell crank into normal locking engagement with the lever 61. The bell 90 crank includes a transversely extending arm or member 69 while the shifter bar 33 has a strike member 70 secured thereto and having an inclined face 71 so that when the same strikes the arm 69 of the bell crank, 95 said arm will be depressed and the locking portion 67 of the bell crank raised, thus releasing the lever 61 and permitting the same to drop by reason of its own weight. Said lever may be provided with a weight 100 or handle 72 at the free end thereof to insure a reliable action of the lever in this 105 respect.

The operation of the machine so far as the locking mechanism is concerned will 110 now be briefly described as follows: Assuming that the locking mechanism has been actuated and is in operation to stop the machine, if it should be desired to again start the machine, it is merely necessary to grasp the handle portion 72 and raise the same to a predetermined extent. The locking portion 66 of the lever will then be operative to pass beneath the adjacent portion of the bell crank and finally the spring 68 will 115 tilt the bell crank into locking engagement with the lever. When this occurs the machine is in position to be started. Assuming now that a skein is being wound upon the reel and the guide 32 and consequently the shifter bar 33 is moving constantly toward the free end of the reel, the arm 70 is moving in that direction likewise and finally comes into abutment relation with the bell crank and due to the steepness of the 120 surfaces 71 will tilt the same the desired 125 130

amount within the space of a movement equal to the pitch of the tooth on the rack 34, causing the lever 61 to be released in the manner described hereinbefore and the machine to be stopped.

While a specific arrangement has been shown and described, it is to be understood that various changes may be made within the scope of this invention. It will be understood particularly that certain features of the invention are applicable for use in connection with a machine that is constructed to procure generally a relative movement between a guide and reel regardless of how such movement may be obtained. Furthermore, the rack 34 may assume various forms or shapes, the teeth, however, being essential in order to secure the intermittent or periodic movement for the sake of obtaining a relative movement as between the guide and the reel. Furthermore, it will be understood that as between the cam 35 and the shifter bar 33, various arrangements are feasible which are operative to secure a relative movement of these members into meshing engagement with each other for intermittent actuation of the bar. Furthermore, the term "cam" as regards the cam 35 is used herein in the broad sense to indicate any means which may be used to actuate the shifter bar. Likewise the means for obtaining a relative movement as between the shifter bar and said cam may take various specific forms such as will be readily understood by those skilled in the mechanical art.

In the employment of this machine for the winding or coiling of ribbon or other species of tapes upon cards or the like, it is customary to simply lay or otherwise place and hold temporarily a card upon or against the arms of the reel so that by the operation of the machine as fully explained above, the commodity will be rolled or wound upon the card until a sufficient amount thereof will be so rolled. The card will then be removed and another one put in place for similar treatment.

I claim:

1. In a tape winder, the combination of a reel, means for rotating said reel to cause tape to be wound thereon, a cam associated with said reel and rotatable by said means, a shifter bar having a guide for laying the tape along the reel as the bar is moved in a direction substantially parallel to the axis of the reel, said bar comprising a plurality of teeth engageable with said cam whereby said bar is moved as aforesaid according to the rotation of said reel, means supporting said bar in movable relation with respect to said cam whereby when the bar is moved away from the cam the tape is wound on the reel at one portion thereof, while when the bar is moved toward and engaged with

said cam, the tape is moved along the reel, and means for moving said bar periodically toward or from the cam according to the number of rotations of said reel.

2. In a tape winder, the combination of a reel, means for rotating said reel, a cam rotatable at the speed of said reel and about an axis parallel to the axis of the reel, a shifter bar for the tape movable longitudinally of the reel when the tape is to be shifted and a new winding formed on the reel, said bar having engaging means, and means for moving said bar periodically into engagement with said cam to cause a movement of the bar as aforesaid.

3. The combination as in claim 2 wherein a shaft is provided for rotating said reel, and said cam is mounted to be supported by said shaft for coaxial rotation with said reel.

4. The combination as in claim 2 wherein said cam is mounted for coaxial rotation with said reel, and the means for periodically moving said bar includes a worm wheel driven by the means for rotating said reel, and a cam actuated by said worm wheel and operative to move said bar periodically toward the first mentioned cam after every predetermined number of rotations of said reel.

5. The combination as set forth in claim 2 wherein said bar is tiltably mounted for movement toward or away from said cam, and the means for moving the bar periodically includes a cam which rotates at a reduced speed with respect to said reel, means being provided for tilting said bar including a follower for said cam.

6. In a tape winder, the combination of a reel, means for rotating said reel to cause tape to be wound thereon, a guide for the tape, and means for causing a movement of the tape along the reel to form different windings of tape thereon including a cam, a member having teeth engageable with said cam to cause endwise movement of the member, said member having constant parallel relation to the axis of the cam and movable bodily toward or from said axis, and means for causing said member and said cam to move toward each other periodically for periodical engagement and co-operation with the guide and the reel to make the cam effective for causing a relative movement between the guide and the reel to move the tape along the reel as aforesaid.

7. In a tape winder, the combination of a reel, means to rotate the same, a shifter member having a guide to lay the tape along the reel, and means for periodically actuating said member including an engaging cam, a rack so arranged with respect to the guide that the cam is operative to vary the relative position of the guide and the reel according to the pitch of said cam, said cam and said rack being relatively movable into and out

of meshing engagement with each other periodically for actuation of said member as aforesaid, and means for causing such relative movement between said cam and said rack into and out of meshing engagement with each other.

8. In a tape winder, the combination of a reel, a shaft for supporting and rotating said reel, a cam rotating with said reel and supported on said shaft, a worm on said shaft, means including a worm wheel operative by said worm and having a second cam rotating at a reduced speed relatively to the first cam, a bar having a guide for laying the tape along the reel, said bar being movable in a direction parallel to the axis of the reel, means for supporting said bar in tiltable position about an axis parallel to the axis of the reel, a follower co-operating with the second cam to tilt said bar, said bar having a rack to engage the first cam when tilted as aforesaid, and means operative to retain said rack away from and out of engagement with the first cam, the first cam being operative to move said bar according to the pitch thereof to cause the guide to supply the tape to another part of the reel.

9. In a tape winder, the combination of a reel, and means to rotate the same, said reel comprising a pair of arms in spaced parallel relation with each other, said arms being grooved along the outer edge surfaces thereof remote from each other whereby a cord can be laid in said grooves to extend along said arms, clamping means for the cord being provided on each arm at a fixed end thereof, while the free end of said arm has a deepened groove formed as an extension of the groove aforesaid, the sides of the deepened groove being bent toward each other to form a reliable spring clamp for the other end of the cord.

10. In a tape winder, the combination of a reel, means to rotate the same, a shifter

bar having a guide to lay the tape along the reel, means to actuate said bar periodically, an arm borne by said bar, a bell crank to be actuated by said arm when said bar has reached its limit of travel, and a tiltable member having means to interlock with said bell crank and having a wedge, the means for rotating the reel having a friction clutch and a member to engage said wedge when said tiltable member drops after the bell crank has been actuated and disengaged from said tiltable member by said arm thus permitting the tiltable member to drop, said wedge engagement rendering the clutch ineffective to transmit power to the reel to rotate the same.

11. In a tape winder, the combination with tape winding means including a reel and a tape guide relatively movable angularly with respect to each other to cause tape to be wound around the reel, of means for causing a relative longitudinal movement between the guide and the reel whereby the tape will be wound along the reel comprising a member having a plurality of teeth, a cam to engage the teeth in succession, said member being movable bodily toward the cam and with its axis in constant parallelism with the axis of the cam to make the pitch of the cam effective to move said member longitudinally, means for periodically engaging said cam with one of said teeth to cause a longitudinal movement as aforesaid after a predetermined number of turns of tape have been formed on the reel to begin a winding of tape at another part of the reel, and means for making the relative longitudinal movement effective to cause a relative longitudinal movement between said guide and said reel for the purpose aforesaid.

In testimony whereof I affix my signature.

HERMAN P. RUF.
